UNITED STATES PATENT OFFICE.

WILLIAM D. LOWRY, OF ST. LOUIS, MISSOURI.

UNDERFRAME FOR CARS AND TENDERS.

No. 922,788.

Specification of Letters Patent.

Patented May 25, 1902.

Application filed July 11, 1900. Serial No. 443,123.

To all whom it may concern:

Be it known that I, WILLIAM D. LOWRY, a citizen of the United States, residing at St. Louis, in the county of St. Louis City and State of Missouri, have invented new and useful Improvements in Underframes for Cars and Tenders, of which the following is a specification.

This invention relates to underframes for cars and tenders and its object is to provide an underframe which can be conveniently made in whole or in part of cast steel sections of standard size and requiring but comparatively few patterns.

15 A further object of the invention is to provide the underframe with roller side bearings of novel construction and which are utilized also to space and assist in securing in position the sections of the transverse members 20 with which they are associated.

In the accompanying drawings illustrating one embodiment of the invention Figure 1 is a plan view of the underframe. Fig. 2 is a longitudinal sectional view on the line 2—2 25 of Fig. 1. Fig. 3 is a sectional view on the line 3—3 of Fig. 1 and showing a side bearing. Fig. 4 is a sectional view similar to Fig. 3 but showing a different form of side bearing. Figs. 5 and 6 are transverse sectional 30 views on the lines 5—5 and 6—6, respectively, of Figs. 1 and 2. Fig. 7 is a detail plan view of a portion of the center sill. Fig. 8 is a detail plan view of a pair of sections.

My invention may be variously embodied 35 with side sills and end sills of different constructions. In the drawings I have shown cast steel end sills 9 and transverse Z-bar side sills 10, the latter carrying the wood side sills 10'.

40 The center sill 11 preferably comprises a single steel casting extending from one end sill to the other, but it may be made in sections if desired. I prefer to make the center sill of inverted U-shape, as shown, with integral center bearings 12 but the particular 45 form of the center sill is not an essential part of the invention.

Transverse members of the underframe, 50 which comprise what are commonly called the body bolsters and cross ties or needle beams, are made in sections and secured to the center sill and side-sills. These sections are made alike so that one pattern can do

for all and each transverse member comprises four sections, two on each side of the 55 center sill and the sections of each pair are spaced apart and rigidly secured as herein-after described.

The center sill is provided at its bottom with outwardly projecting side flanges 13 60 which may extend from end to end of the center sill to stiffen and strengthen the same. The center sill is also provided with integral side lugs 14 at its top and at intervals between its ends and corresponding lugs 14' 65 are provided on the sides of the center sill beneath the lugs 14 and between the center bearings.

The body bolsters each comprise four cast steel sections 15 which are arranged in pairs 70 on opposite sides of the center sill with the sections separated in or about the manner shown in Fig. 1. The outer ends of these sections 15 are fastened to the side sills 10 and the inner ends of the said sections are 75 fastened to the lugs 14 and to the flanges 13 (Fig. 5). I prefer to provide an offset 15' at the upper inner corner of each section 15 to receive the lug 14 so that the top of the body bolster sections may lie in a plane with the 80 top of the center sill.

A cover plate 16 is preferably arranged across the center sill to overlap the lugs 14 and is fastened to said lugs and the inner ends of the sections by the rivets or bolts. 85

I may make the cross ties of a plurality of sections like the body bolsters but this is not absolutely essential and they may be made in a different manner if desired. However, I prefer to make each cross tie, and as many 90 may be used as found desirable, of four sections 17 similar to the sections 15 of the body bolsters and secured at their outer ends to the side sills and at their inner ends to the lugs 14 and 14' (Fig. 6). These cross tie sections are also offset at 17' to receive the lugs 14 and cover plates 18 like the cover plates 16 on the body bolsters are also provided. 95

The sections of each pair in the several transverse members of the underframe are 100 preferably connected between their ends to brace and strengthen and hold them properly, spaced apart. The sections 17 of the cross ties may thus be connected by plates or bars 19 of any suitable size and shape (Fig. 1). 105 I prefer, however, to make the connections

between the sections of each pair comprising the body bolsters in the form of side bearings, and each may consist of a plate or bar 20 shaped as shown in Fig. 4 to make a side bearing for the underframe. However, I prefer to provide a roller side bearing and this may consist of a steel casting 21 provided with end lugs 21' to receive the rivets or bolts whereby the bearing casting is fastened to the sections 15. This bearing casting has a transverse central opening 22 of the general shape of an inverted triangle. A roller 23 is housed within the bearing casting and is inserted through a slot 24 in the bottom thereof and afterward is provided with an axle 23' and projects beyond both sides of the roller to engage the inclined walls 22' at the bottom of the opening 22. The roller is adapted to travel back and forth in the opening 22 against the top of the bearing casting when the weight of the car rests thereon, but when the weight of the car is removed the roller will return to its normal position centrally disposed within said opening, the axle then traveling on the inclined walls 22'. Either the side bearing 20, shown in Fig. 4, or the roller side bearing, shown in Fig. 3, may be used in my improved underframe or any other form of side bearing adaptable to the underframe may be used. The side bearing spaces the sections the proper distance apart and stiffens and strengthens the same. The transverse member sections 15 and 17 may be made in any suitable shape but I prefer to make them in the general form illustrated in the drawings for they can then be cast without the use of a core. These sections may be provided with lugs 25 to support the stringers 26. Diagonal braces 27 may be provided at the ends of the underframe if desired. The preferred form of the transverse members is that of a channel with closed ends as illustrated and each member comprises a top 28, a bottom 29, a side 30 and ends 31 and 32, all cast in one piece.

My improved underframe is simple in construction and the cost of manufacture is considerably reduced by reason of the simplicity 50 in the form and construction and particularly because the parts are of standard size and shape. This enables the cast parts to be made with but few patterns and without the use of cores. Thus the end sills are made 55 alike of one pattern, the sections of the body bolsters are made alike from one pattern, the side sills are made alike of rolled pressed or cast metal and the center sill, in the preferred form illustrated, is a single casting. 60 The fact that all of the transverse member sections are made alike is of material importance in the matter of repairs for a single section may be used in any transverse member within the underframe.

What I claim and desire to secure by Letters Patent is:

1. In an underframe for cars and tenders, the combination of a cast steel center sill made in inverted U-shape in cross section, a center bearing integral with said center sill, 70 and a transverse member comprising two pairs of oppositely disposed cast steel sections secured at their inner ends to the center sill and arranged on opposite sides of said center bearing.

2. In an underframe for cars and tenders, the combination of a center sill, side flanges and side lugs on the center sill, and a transverse member comprising two pairs of oppositely disposed cast steel sections secured at 80 their inner ends to said lugs and flanges.

3. In an underframe for cars and tenders, the combination of a cast steel center sill, side lugs on the center sill and integral therewith, and a transverse member comprising 85 two pairs of oppositely disposed cast steel sections secured at their inner ends to the center sill between said lugs.

4. In an underframe for cars and tenders, the combination of a cast steel center sill, 90 side lugs on the center sill integral therewith at the top thereof, a transverse member comprising two pairs of oppositely disposed cast steel sections secured at their inner ends to the center sill beneath said lugs, said sections 95 being offset to receive said lugs, and a cover plate extending across the center sill and over a pair of oppositely located lugs and secured thereto.

5. In an underframe for cars and tenders, a transverse member comprising two pairs of separate cast steel sections, the sections in each pair being spaced apart, and a roller bearing connected to each pair of sections and located therebetween.

6. In an underframe for cars and tenders, a transverse member comprising two pairs of separate cast steel sections, the sections in each pair being spaced apart, and a roller bearing comprising a casting fastened to each pair of sections and having a transverse opening therein, and a roller loosely arranged in said opening and having a bearing against the top of the casting.

7. In an underframe for cars and tenders, a transverse member comprising two pairs of separate cast steel sections, the sections in each pair being spaced apart, and a roller bearing comprising a casting fastened to each pair of sections and having a transverse opening of generally inverted triangular shape, a roller loosely arranged in said opening and having a bearing against the top of the casting, and an axle projecting from both sides of the roller.

8. In an underframe for cars and tenders, a transverse member comprising two pairs of separate cast steel sections, the sections in

each pair being spaced apart, and a roller bearing comprising a casting fastened to each pair of sections and having a transverse opening therein of generally inverted triangular shape, a slot in the bottom of the casting communicating with said opening, a roller adapted to be inserted through said slot into the opening and to work loosely in said

slot and opening, said roller having a bearing against the top of the casting, and an axle 10 projecting from both sides of the roller.

WILLIAM D. LOWRY.
